UNITED STATES PATENT OFFICE.

ELLIS MICHAEL, OF LAPORTE, INDIANA, ASSIGNOR TO ANDREW FREE AND JOHN W. FREE,
OF SAME PLACE.

GRAIN-SEPARATOR.

Specification of Letters Patent No. 31,096, dated January 8, 1861.

To all whom it may concern:

Be it known that I, ELLIS MICHAEL, of Laporte, in the county of Laporte and State of Indiana, have invented a new and Improved Grain-Separator; and I do hereby declare that the following is a full, clear, and exact description of the same, reference being had to the annexed drawing, making a part of this specification, in which—

10 Figure 1, is a side sectional view of my invention, taken in the line *x*, *x*, Fig. 3. Fig. 2, a transverse vertical section of the same, taken in the line *y*, *y*, Fig. 1. Fig. 3, a plan or top view of the same with the 15 hopper removed.

Similar letters of reference indicate corresponding parts in the several figures.

To enable those skilled in the art to fully understand and construct my invention, I 20 will proceed to described it.

A, represents a box or case which may be constructed in much the usual way to receive and hold the working parts of the machine.

B, is a hopper which is placed on the 25 upper part of the box or case A, and is provided with a slide *a*. In the box or case A and directly underneath the hopper B, a shoe C is placed. This shoe is suspended in the box or case by rods *b*, *b*, at its front 30 part, one at each side, and by a hook *c*, at its back part, at the back end of the box or case there is a fan D from one end of the shaft *d*, of which, a shake motion is given the shoe C, by an eccentric *e*, connecting rod *f*, bell 35 crank *g*, and shackle *h*, all of which are shown in Fig. 3.

In the upper part of the shoe C, at its inner end there is an inclined apron E, which has ribs or slats *i*, attached to it, said 40 ribs or slats diverging from their inner ends, as shown clearly in Fig. 3. The inner ends of the ribs or slats *i*, extend from a point directly underneath the discharge orifice of the hopper.

45 F, is a coarse screen which is placed in the upper part of the shoe C. This screen is slightly inclined, and its inner end, which is the most elevated, is in contact with the outer end of the apron E. In the shoe C, 50 and underneath the inner part of the screen F, there is a box G, the bottom of which is formed of two inclined parts as shown clearly in Fig. 2. This box G is closed at both its front and back ends, and is placed 55 in the shoe in an inclined position parallel

or nearly so, with the screen F as shown clearly in Fig. 1. The top of the box G, is formed of a fine screen G' of a size sufficient to allow grass seed to pass through, but to exclude grain. To the lower and 60 outer end of the box G, a tube H, is attached, said tube extending through the side of the shoe C, and having its end directly over a box I, which is attached to the inner side of the box or case A, and has a discharge opening *j* made in its lower end, said opening being shown clearly in Fig. 2.

The screen G' has parallel ribs or slats *k*, placed on it, the inner ends of which are in line or coincide with the outer ends of the 70 ribs or slats *i*, of the apron E. In the shoe C, directly in front of the box G, there is a chess board J. This board is provided with longitudinal and parallel ribs or slats *k'* attached to it at points in line with the ribs or 75 slats *k*, of the screen G'. Between the outer end of the box G, and the inner end of the chess-board J, there is a space *l*.

In the lower part of the shoe C, there is placed an inclined screen K, the inner end 80 of which is the depressed or lower end, as shown clearly in Fig. 1. This screen has an inclined side-piece *m*, attached to each side of it, the form of which is shown clearly in Fig. 2. At the outer end of the screen K, at 85 each side, there is a pin *n*, projecting horizontally, and these pins are fitted in notched plates *o*, *o*, one at each side of the shoe C. The inner and lower part of the screen K, rests on a bar L, which is placed in the inner 90 part of the shoe C, and has its ends secured thereto by pivots *n*. To the under side of the bar L, near one end a hook *q'* is attached, said hook being connected by a bar *r*, to the box or case A as shown at *s*. In the bottom 95 plate or board *t*, of the shoe C, there are openings *u*, which are directly over a box M.—see Fig. 1.

N is an inclined board which forms the bottom of the box or case A, directly back 100 of the shoe, and *v*, is an opening at the lower end of said board, the opening extending the whole width of the box or case.

O, O', are partition or "bluff-boards" 105 which serve to prevent the escape of wind from the fan at each side of the shoe, so that the full force of the blast generated by the fan will pass through the shoe C. The partition or board O, however does not extend down as low as the other one O', and a 110

space w , is thereby allowed to permit a passage of air directly over the box I, as indicated by the arrow 1, in Fig. 1.

- The operation is as follows: The fan-shaft d , is rotated by any convenient power, and the grain to be operated upon, is poured into the hopper B, and is allowed to pass on the apron E in greater or less quantities by regulating the slide a . The apron E, conducts the grain to the screen F, and the ribs or slats i of the apron, aided by the shake motion of the shoe, spread the grain so that it will extend over the screen F its whole width. The large foreign substances are separated from the grain by this screen F and pass off its outer and lower end. The grain, grass-seed and other small foreign substances pass of course through the screen F and fall in the fine screen G' of the box G. The grain is kept in a spread state in screen G' by means of its ribs or slats k , and the grass-seed passes through screen G' into the box G and from thence through the tube H into the box I, all light foreign substances being expelled from it by the blast which passes over the box I, as indicated by the arrow 1. The sound grain passes down through the opening l , and is subjected for the first time to a blast from the fan D. This blast throws the chess off the board J, while the sound grain passes down in the screen K and inclined board N and is discharged through the opening v . Small impurities and light grain that may have casually passed over the screen G', will pass through screen K, and through the openings u , u , in the box M, and all light impurities such as dust, etc. will be effectually expelled by the blast. The red arrows, Fig. 1, indicate the direction of the sound grain through the machine. The blue arrows, Figs. 1 and 2 show the passage of the grass-seed and the black dotted arrows, show the direction of the light imperfect grain.

By this arrangement it will be seen that the grass-seed is separated from the grain

before the latter is subjected to the blast, and the efficiency of the latter will therefore be greatly enhanced, as the mass of material to be acted upon by the blast is considerably reduced, besides the grass-seed will be separated in a more perfect manner. In consequence of having the ribs or slats i , k , k' , attached to the upper surfaces of the apron E, screen G', and chess-board J, the grain is made to pass over said parts in a spread state or in a thin layer, so as to pass over the screens F, G' in a manner to be most effectually operated upon, and the grain also presented in a spread state to the action of the blast. By having the inner part of screen K, rest on the bar L, and the latter hung on pivots p , p , and connected to the box or case by the hook q , and rod r , a vertical shake motion is given the screen K in addition to the shake motion it receives in common with the shoe C, and said screen is effectually prevented from choking or clogging. By having the outer part of the screen K, fitted in the shoe C, by means of the pins n , fitting in notched plates o , o , a greater or less inclination as may be desired may be given the screen without changing the position of the shoe.

I would remark that when the grain contains grass seed, and the box G used, the chess-board J may be removed entirely from the shoe, and when the seed box is not required, it may be removed, and the chess-board J shoved back in the place occupied by the shoe.

Having thus described my invention what I claim as new and desire to secure by Letters Patent, is—

The slats i , k , k' , placed respectively on the apron E, screen G' and chess board J, where said parts are arranged relatively with each other, the fan D, and the screen F, to operate as and for the purpos set forth.

ELLIS MICHAEL.
